UNITED STATES PATENT OFFICE.

EUGENE M. FARR, OF WASHINGTON, DISTRICT OF COLUMBIA.

AERIAL VESSEL.

SPECIFICATION forming part of Letters Patent No. 678,114, dated July 9, 1901.

Application filed February 19, 1900. Serial No. 5,839. (No model.)

To all whom it may concern:

Be it known that I, EUGENE M. FARR, a citizen of the United States, residing at Washington, in the District of Columbia, have invented 5 a certain new and useful Aerial Vessel, of which the following is a specification, reference being had therein to the accompanying drawings.

This invention relates to aerial vessels for 10 the purpose of navigating the air; and one of the principal objects of the invention is to provide a combined balloon and aeroplane so constructed that it may be readily converted from a balloon into an aeroplane, or vice versa, thus 15 enabling the same part of the apparatus to be utilized for ascending to the desired height and subsequently collapsed, partially or wholly, and employed as an aeroplane, which as the machine is propelled serves to maintain the 20 said machine in the air, owing to the resistance of the air against the inclined surface of the aeroplane. In connection with the combined balloon and aeroplane means are provided 25 for inflating and deflating the same and additional means for facilitating the collapse of the balloon and holding it in its collapsed condition.

Another object of the invention is to provide, in connection with the balloon and aeroplane 30 and in connection with a car supported beneath the same, improved propelling devices for the machine as a whole, the said propelling devices being in the form of screws of considerable length having continuous spiral 35 webs or blades and arranged on opposite sides of the car suspended below the balloon.

Other objects and advantages of the invention will appear in the course of the ensuing description.

40 The invention consists in certain novel features and details of construction and arrangement of parts, as hereinafter fully described, illustrated in the drawings, and incorporated in the claims.

45 In the accompanying drawings, Figure 1 is a perspective view of a machine constructed in accordance with this invention, showing twin screws at each side thereof. Fig. 2 is a side elevation of the same, showing the balloon inflated. Fig. 3 is a similar view show-

ing the balloon deflated and adapted for use as an aeroplane and also showing a single screw in place of the twin screws. Fig. 4 is a vertical cross-section through the machine.

Similar numerals of reference are employed 55 to indicate corresponding parts in all the figures of the drawings.

The machine contemplated in this invention comprises a combined balloon and aeroplane, in the construction of which I employ a 60 stiff bottom wall 1, which is preferably formed of aluminium and which may be braced or reinforced and stiffened in any approved manner. The plate 1 is for the greater portion of its length straight or flat, while the end portions 2, forming the bow and stern, are curved or deflected upwardly, terminating at the points 3. The upper wall of the balloon also consists of a similar plate 4, which is straight or flat through the major portion of its length, 65 the ends being slightly deflected or curved downward. Both of the plates 1 and 4 are substantially rectangular; but the top plate 4 is shorter than the bottom plate, as clearly shown in Figs. 2 and 3. The side edges of 70 the top plate 4 are preferably bent downward, so as to provide rounded surfaces, which 75 will avoid wear on the ropes hereinafter referred to.

The side walls 5 of the balloon consist of 80 any suitable flexible material united by an air-tight joint to the top and bottom plates. Similar fabric or flexible material is employed to form the end continuations 6 of the top plate 4, so that when the balloon is inflated 85 it resembles in longitudinal section or side elevation a double-pointed cigar. The deflected portions 2 of the bottom plate are designed to act as aeroplane-surfaces after the balloon is collapsed in the manner hereinafter 90 described.

Suspended beneath the balloon is a car 7 of sufficient size to comprise a saloon or cabin 8, an upper open deck 9, surrounded by rail 10, and a lower room or hold 11, in which is 95 arranged an engine or suitable motor 12, by means of which the machine is propelled, and in which may be located the gas-generators for inflating the balloon. The car is provided at its advance end with a sharpened 100

bow 13 in order to facilitate its progress. Projecting downward from the bottom of the car is a longitudinal fin 14, which tends to keep the machine in a straight line. At opposite sides of the car are arranged cylinders 15, which form housings for Archimedean propelling-screws 16. Preferably I employ twin screws 16 at each side of the car, with a separate cylindrical housing 15 for each screw. Where two screws are employed, they are mounted upon a common shaft 17, which is provided about midway the length of the machine with a band-pulley 18, around which passes a driving-belt 19, connecting with the motor 12 within the car. The side walls of the hold 11 may be utilized to constitute parts of the cylindrical housings 15, the said side walls converging downwardly and being curved for that purpose, as shown in Fig. 4.

Instead of providing twin screws at each side of the machine a single long screw may be employed, as shown in Fig. 3, in which event the pulley 18 will be located at one end of the shaft, as illustrated in said Fig. 3.

25 25 designates a rudder, by means of which the machine may be steered.

In connection with the balloon I employ a series of reefing-ropes 20, the upper portions of which are bifurcated, as shown at 21, and connected to ropes 22, which pass transversely across the top plate 4. The ropes 20 extend downward to the car, so that they may be drawn downward and fastened for collapsing the balloon and holding the same in its collapsed condition.

23 and 24 designate inflating and deflating tubes or pipes, respectively, which extend downward to the car. The inflating-pipe may 40 be connected with any suitable generator for supplying gas to the balloon when it becomes necessary to inflate the same. When the balloon is inflated, it assumes the shape illustrated in Figs. 1, 2, and 4, and the parts will 45 be so proportioned that the balloon when inflated will afford the necessary buoyancy to raise the machine as a whole to any desired elevation. When the desired elevation is attained, the engine is started, and when the 50 machine attains the necessary velocity in order to increase the speed of the machine and reduce the area of resistance of the balloon the latter is partially deflated and the reefing-ropes drawn downward and secured, 55 so as to hold the top plate 4 in the position shown in Fig. 3, in which position the upper portion of the balloon, including the top plate, is brought below a line drawn through the points 3. When the balloon is thus collapsed or partially collapsed, the bottom plate 1 acts as an aeroplane, the resistance of the air against the forward upturned or inclined portion of the plate 1 acting to prevent the machine from descending. Descent may be 60 accomplished by decreasing the speed of the 65

propellers or by partially inflating the machine and stopping the propellers

In connection with the balloon and aeroplane I may employ means for pivotally mounting the bottom plate of the balloon 70 with relation to the car and other means for adjusting and varying the angle of the bottom plate 1 with relation to the car, which will make it possible to ascend or descend at any desired angle.

I do not desire to be limited to the details of construction hereinabove set forth, but reserve the right to change, modify, or vary the construction within the scope of this invention.

Having thus described the invention, what is claimed as new, and desired to be secured by Letters Patent, is—

1. In aerial vessels, the combination with a collapsible balloon, of an aeroplane forming 85 one of the balloon-walls, substantially as described.

2. An aerial vessel comprising a collapsible balloon having a stiff wall forming, when the balloon is collapsed, an aeroplane, substantially 90 as described.

3. In aerial vessels, the combination with an aeroplane, of a horizontally-elongated collapsible balloon attached throughout its 95 length thereto and having one of its walls formed by the aeroplane, substantially as described.

4. In aerial vessels, the combination with an aeroplane, of a horizontally-elongated collapsible balloon attached throughout its 100 length and width to the upper side thereof, the aeroplane constituting one of the balloon-walls, substantially as described.

5. The combination with an aeroplane having a flat body portion with an upturned forward portion, of a collapsible balloon attached thereto and adapted to fold below the horizontal plane of the forward edge of the aeroplane, the aeroplane forming the bottom wall 105 of the balloon, substantially as described.

6. The combination with an aeroplane consisting of a flat body with upwardly-deflected front and rear end portions, of a collapsible balloon arranged to fold below the plane of the front and rear edges of the upwardly-deflected portions of the aeroplane, the aeroplane forming the bottom wall of the balloon, substantially as described.

7. The combination with an aeroplane consisting of a flat body with upwardly-deflected front and rear end portions, of a collapsible balloon connected therewith and adapted to be housed below the plane of the edges of the upwardly-deflected end portions, and reefing means for securing the balloon when partially 120 or wholly collapsed, the aeroplane forming one of the balloon-walls, substantially as described.

8. The combination with a collapsible balloon having flexible sides, of an aeroplane of 125

stiff material forming the bottom wall of the balloon, a stiff top or upper wall for the balloon, and reefing-ropes associated with said top wall for drawing the top wall toward the bottom wall, substantially as described.

5 9. A collapsible balloon comprising a stiff lower wall forming an aeroplane, a stiff top wall, and flexible sides connecting the top

and bottom walls, substantially as described.

In testimony whereof I affix my signature in presence of two witnesses.
